United States Patent Office.

ALMON D. MANLEY, OF WASHINGTON, MICHIGAN, ASSIGNOR TO HIMSELF AND LEWIS H. CANTINE.

Letters Patent No. 77,629, dated May 5, 1868.

IMPROVEMENT IN HOISTING AND TRANSFERRING-PULLEYS.

The Schedule referred to in these Letters Patent and making part of the same.

TO ALL WHOM IT MAY CONCERN:

Be it known that I, ALMON D. MANLEY, of Washington, in the county of Macomb, and in the State of Michigan, have invented a new and useful Improvement in Hoisting and Transferring-Pulleys; and do hereby declare that the following is a full, clear, and exact description thereof, reference being had to the accompanying drawings, and the letters of reference marked thereon.

In the annexed drawings, making a part of this specification, A represents a suitable frame, composed of a horizontal beam, supported upon legs therefor, and B represents a peculiar-shaped head-block, made substantially in the form shown in the drawings. The head-block B is suspended beneath the beam of the frame A by means of slots in the upper side thereof working on and catching over headed bolts or screws which project downward from the frame A.

A winding-drum, K, is adjusted in the head-block B, for the purpose of tightening a rope, C, which I call the track-rope, and a pulley, R, in the lower part of the head-block, below the rope C, over which a draught-rope or cord, F, passes.

The head-block is made double, or so as to receive the pulley-block D between the sides, and is provided with projections or rests, on which the inclined ways h work when the pulley-block D is drawn up into it. The head-block is further provided with notches or catches on the inside, and near the bottom of its sides, in which the end or catch on the end of the small lever j is caught, when the pulley-block D is drawn up into the head-block B.

K represents a winding-drum, adjusted loosely on its shaft, so that it will slip laterally thereon, so as to keep the rope always in a line with the middle of the head-block when winding up the same. Said drum is provided with ratchet-teeth, on a flange at one end thereof, as is fully shown, by which means it is operated and held in place.

The winding-drum K is turned, and the track-rope thereby tightened, by means of a lever, L, made for the purpose. Said lever L is provided with two lips or projections from one side and end thereof, as is shown in Figure 3, one of which catches inside the rim of the wheel or drum, and the other in the teeth thereof, and thereby locks with and turns the same.

The winding-drum K is provided with a notch or bite, b, in which a rope may be readily secured at any time without tying the same.

The track-rope C is secured, at one end, in the frame A, and extends across to the head-block B, and through between the arms which support the pulley R, and to the winding-drum K, where it is caught in the notch b, and then tightened by means of the lever L and drum B.

D represents a pulley-block or car, which is suspended and works upon the track-rope C, and is operated or moved forward by means of power attached to the draught-rope F. The car or pulley-block D is made in two parts, and hinged together just below the track-rope C. The upper part of the pulley-block D is provided with ways, h, on each side, which fit and work up in the head-block B, on suitable rests therefor.

N represents a small lever or catch, which is pivoted in one end of the lower part of the pulley-block, the end of which is made concave, so as to fit over a rope, E, as is shown. Said lever is also provided with a projection or tongue, which fits in the groove, e, of the sliding bar g.

E represents a rope, to which is attached the weight w, at one end, and passes thence up over the pulley P, and out to the end of the frame A, and there secured. The rope E is made of any length desired, and regulated, as may be required for length, over a pulley in a slot in the end of the frame A.

A small collar, z, is fastened to the rope E, near where the weight is attached, which is caught by the lever N, and the weight is thereby held up when once elevated.

g represents a movable bar, made in the form shown, provided with shoulder or catch i, groove or notch e, and bevelled projection z.

By attaching power to the draught-rope F, and drawing the car or pulley-block D forward, it will be seen that the weight will be elevated, and, as the rope E is taken up, the collar z will pass up and against the catch or shoulder i, when the lever N is drawn over, by means of its tongue working in the groove e, and, at the same time, the bevelled projection z throws up the end of the lever j, and its jaws or catches down, so that, as they pass into the head-block B, they catch in the recesses or notches therefor.

H represents an adjustable collar, for the purpose of stopping and holding the car or pulley-block D from running too far back when loosened from the head-block B. Said collar H is made with a small plate, m, which is pressed firmly against the rope by means of the double elbow-lever l, as shown in the drawings.

The lever l, and thereby the collar H, may be moved or operated by means of a hand-cord, I.

When the pulley-block D runs out, and strikes against the lever l of the collar H, the sliding bar g is thrown or pressed back, and thereby the lever N is detached from the collar z, and the weight then falls down without obstruction.

Having thus fully described my invention, what I claim as new, and desire to secure by Letters Patent, is—

The arrangement of the block B, drum K, pulley R, and lever L, in combination with the car D, and its pulleys, levers N and j, sliding bar g, pulley P, and cords E C F, adjustable collar H, and weight w, the various parts being constructed and operating substantially as set forth.

In testimony that I claim the foregoing, I have hereunto set my hand and seal, this 28th day of January, 1868.

ALMON D. MANLEY. [L. s.]
